UNITED STATES PATENT OFFICE

EZRA B. SMITH, OF CHICAGO, ILLINOIS, ASSIGNOR TO JERSEY SWEeper COMPANY, OF CHICAGO, ILLINOIS, A CORPORATION OF ILLINOIS.

FASTENING AND ATTACHING DEVICE FOR CARPET-SWEeper BAGS.

1,184,038.

Specification of Letters Patent.

Patented May 23, 1916.

Application filed September 19, 1913, Serial No. 790,614. Renewed February 10, 1916. Serial No. 77,524.

To all whom it may concern:

Be it known that I, EZRA B. SMITH, a citizen of the United States, residing at Chicago, county of Cook, State of Illinois, have 5 invented a certain new and useful Improvement in Fastening and Attaching Devices for Carpet-Sweeper Bags, and declare the following to be a full, clear, and exact description of the same, such as will enable 10 others skilled in the art to which it pertains to make and use the same, reference being had to the accompanying drawings, which form a part of this specification.

A common attachment for small vacuum 15 cleaners or sweepers is a dust-collecting bag into which the dirt-laden air is carried and by which the dirt is strained from the air. These bags must be emptied frequently and, because the dirt and lint which they receive 20 has a tendency to adhere to the interior of the bags, it is desirable that the bags be wholly detachable so that they can readily be cleaned.

One of the objects of my invention is to 25 produce a simple and novel closure for a bag opening which will effectually close the mouth of the bag and at the same time permit the bag to be opened or closed quickly and conveniently.

30 A further object of my invention is to produce a simple and novel attaching device for detachably securing one end of a bag to the handle of a sweeper.

A further object of my invention is to produce 35 a simple and novel device for effectively securing the inlet end of a bag to the discharge side of a vacuum cleaner or sweeper.

The various features of novelty whereby 40 my invention is characterized will herein- after be pointed out with particularity in the claims; but, for a full understanding of my invention and of its objects and advantages, reference may be had to the following detailed description taken in connection with 45 the accompanying drawings, wherein:

Figure 1 is a side elevation of a bag equipped in accordance with one form of my invention, together with fragments of a sweeper handle and of a discharge conduit, 50 and the means for attaching the bag to the handle and the conduit; Fig. 2 is a view looking toward the right from the left hand side of Fig. 1; Fig. 3 is a longitudinal section on an enlarged scale through the coupling be- 55 tween the inlet end of the bag and the out-

let end of the sweeper; Fig. 4 is a view on an enlarged scale of a portion of the handle of a cleaner and the attaching means between the handle and the bag, the head of the holding screw being cut away; Fig. 5 is 60 a section on line 5—5 of Fig. 4 including in addition to the parts shown in Fig. 4, the upper end of the bag; Fig. 6 is a top plan view on an enlarged scale of the mouth of the bag and the closing means therefor; Fig. 7 is a view on an enlarged scale of one corner of the bag adjacent to the mouth thereof, showing the condition of the parts when the closing device is released so as to permit it to be removed; Fig. 8 is a section on line 8—8 of 70 Fig. 6; Fig. 9 is a view similar to Fig. 4, showing a modification; and Fig. 10 is an edge view of the upper end of the clip shown in Fig. 9.

Referring to Figs. 1 to 8 of the drawings, 75 1 represents a bag of any suitable construction, that illustrated being of the type ordinarily employed as dust-collecting bags on vacuum cleaners or sweepers. In accordance with my invention I form a bead, 2, around 80 the mouth of the bag, this being conveniently accomplished by folding the fabric at the mouth down over a cord, 3, or other suitable thickening device. The closing element is in the form of a tube, 4, having a length equal 85 to the width of the mouth of the bag and slit longitudinally on one side so as to permit it to be slipped over the flattened end of the bag with the beads lying in the interior of the tube. The slit or slot in the tube is made 90 wide enough to receive the double thickness of material of the collapsed bag, but narrower than the combined widths of the two beads at the ends of the two collapsed sides and consequently the tube can be withdrawn 95 only by moving it lengthwise. As long as the tube is prevented from moving lengthwise it will hold the mouth of the bag securely closed.

In accordance with my invention I provide 100 a simple means for locking the tube on the bag, this consisting simply of a bridle or bail, 5, having its ends attached at opposite sides of the mouth of the bag. By flattening 105 the bag so that the ends of the bridle will be at opposite ends of the flattened portion, slipping the closing tube in place, and then hanging up the bag by the bridle, the ends of the bridle engage with the ends of the closing tube and prevent it from slipping from 110

the bag. The locking of the tube may be made more secure by cutting notches, 6, in the ends of the tube, the lower ends of the bridle entering these notches and preventing 5 the bridle from slipping transversely and releasing the tube.

It will thus be seen that the bag is opened by the simple act of slipping off the tube after the bridle has been allowed to drop 10 down out of the way, and it is closed and locked by the simple acts of slipping the tube in place and hanging the bag up by the bridle.

It is also desirable to have means for 15 holding the bridle so that it will not accidentally be released but may be quickly attached or detached when desired. To this end I have provided a wire clip, 8, having a U-shaped bend, 9, at the middle and eyes, 10, at the ends. The bridle is passed through the eyes in the clip and the U-shaped member is adapted to be slipped down over a suitable headed stud, 11, on the handle, 12, of the sweeper or other supporting member. The arms of the U-shaped member 9 of the clip are bent so as to be closer together at the middle than at the ends, thus making the member 9 act as a 25 spring catch whose arms will be spread apart by the act of pressing it upon the stud and spring back again when the stud reaches the widened space in the closed end of the U-shaped member.

In some cases I prefer to make the clip 30 in the form shown in Figs. 9 and 10, the clip comprising a U-shaped portion, 14, the free ends of whose arms, 15, are crossed and provided with eyes, 16. The opening between the upper portions of the U-shaped member is narrower than the diameter of 35 the head of the stud 11, but just before the arms are crossed they are bent outwardly so as to provide a large opening, 17, through which the head of the stud may pass. In other words, the opening in the U-shaped member 14 is in the form of a keyhole slot. The upper end of the clip is preferably bent laterally as indicated at 18 so as to provide 45 a finger piece by means of which the clip may be lifted to disengage it from the supporting stud. If desired, the bridle may be knotted between the eyes 16, as indicated at 50 so as to prevent the bridle from sliding in the clip.

55 It will be seen that in each of the two forms of clip illustrated, the bridle is detached by the simple act of lifting the clip from the supporting stud, but will not accidentally become detached because the weight of the bag holds it in the locked position.

In Figs. 1, 2 and 3 I have illustrated a simple and reliable connection between the inlet end of the bag and the discharge side 65 of the cleaner or sweeper. 25 represents the

outlet end of a discharge conduit and at some distance from the mouth thereof is an annular exterior flange, 26. Within the inlet end of the bag is clamped a sleeve, 27, adapted to fit snugly upon the end of the member 25 above the flange. On the member 25 below the flange 26 is a tooth or projection, 28, and on the lower end of the bag is a resilient bail, 29, in the form of a tightly coiled helical spring. To connect the bag 70 to the discharge side of the sweeper the sleeve 27 is slipped down over the end of the member 25 and the spring bail is then sprung over the tooth or projection 28 causing the lower end of the sleeve to be drawn 75 against the flange and making a tight joint between the member 25 and the bag. The bag may conveniently be clamped about the sleeve 27 by means of a metal band, 30, whose ends are connected by a screw bolt, 80 31, or other adjustable device. The band may also be used to fasten the ends of the spring bail in place, the ends of the bail being placed between the band and the fabric of the bag so that the act of tightening the 85 band to secure the bag on the sleeve serves also to lock the ends of the bail securely to the bag.

It will thus be seen that I have provided a simple and effective device for attaching 90 the bag to the discharge side of a cleaner or sweeper; the bag being securely fastened in place by the mere act of slipping the lower end upon the outlet conduit of the sweeper and springing the bail over the 95 tooth or projection; and the bag being removed by the simple acts of slipping the bail from the tooth or projection and lifting the bag.

I claim:

1. In combination, a bag having a thickened edge at the mouth, and a longitudinally-slotted tube adapted to be slipped over the end of the bag when the latter is flattened, and a bridle connected to the bag 100 at opposite sides thereof and adapted to engage with the ends of the tube when the bag is suspended from the bridle.

2. In combination, a bag having a thickened edge surrounding the mouth, a slotted tube adapted to be slipped in the direction of its length over the engaging thickened edges of the collapsed mouth, and a bag-suspending device adapted to engage said tube 115 and hold it on the bag.

3. In combination, a bag having a thickened edge surrounding the mouth, a slotted tube adapted to be slipped in the direction of its length over the engaging thickened edges of the collapsed mouth, and means on 120 the bag for engaging with the tube to prevent the latter from moving relative to the bag.

4. In combination, a bag having a thickened edge at the mouth, a slotted tube 130

adapted to be slipped in the direction of its length over the engaging thickened edges of the collapsed mouth, and a member connected to opposite sides of the bag and adapted to extend over the ends and across the top of the tube to hold the latter on the bag.

5. In combination, a bag having a thickened edge at the mouth, a slotted tube adapted to be slipped in the direction of its 10 length over the engaging thickened edges of the collapsed mouth, the ends of the tube

being notched, and a member connected at opposite sides of the bag and adapted to extend outwardly across the tube and 15 through the notches in the latter to hold the tube on the bag.

In testimony whereof, I sign this specification in the presence of two witnesses.

EZRA B. SMITH.
